UNITED STATES PATENT OFFICE.

WILLIAM KLOCHE, OF NEW YORK, N. Y., ASSIGNOR TO E. W. BLISS COMPANY, OF BROOKLYN, NEW YORK, A CORPORATION OF WEST VIRGINIA.

DRAWING-PRESS.

1,206,859.

Specification of Letters Patent.

Patented Dec. 5, 1916.

Application filed March 8, 1916. Serial No. 82,850.

To all whom it may concern:

Be it known that I, WILLIAM KLOCHE, a citizen of the United States of America, residing in the borough of Brooklyn, county of Kings, in the city and State of New York, have invented certain new and useful Improvements in Drawing-Presses, of which the following is a specification.

My invention relates to presses, and particularly to drawing presses adapted to draw shells of various shapes from metal blanks. In presses of this character if the punch presses the blank directly into the die, the blank is very apt to bow out at its lower part, producing surplus metal at the bottom of the stamping which will subsequently have to be pressed out flat. To avoid this a presser-foot has been used which came up and engaged the blank beneath the punch and held the two in firm contact during the forming operation. The presser-foot was then pressed up with the work and punch and acted as a knock-out and discharged the work from the die when the punch was withdrawn. This caused the stamping to adhere to the punch and it was separated from the punch with strippers, frequently causing damage to the stamping or to the strippers during this operation.

The object of the present invention is to provide a construction of machine wherein the presser-foot or blank-holder is caused to firmly clamp the work against the punch or plunger during the drawing operation and prevent the presence of any surplus metal at the bottom of the stamping. Thereupon, after the plunger is withdrawn from frictional contact with the stamping, the blank-holder, by an independent motion, discharges the stamping from the die.

In carrying this invention into effect my invention consists in providing means whereby the blank-holder is given a motion during the drawing operation in unison with the movement of the plunger, and after the plunger is withdrawn, in giving the blank-holder an independent movement whereby the stamping is discharged from the die.

In the accompanying drawing I have illustrated a desirable form in which my invention may be embodied.

In said drawing, Figure 1 represents a side view, partly in section, of a drawing press containing my invention; Fig. 2 is

an end view thereof, partly in section, on the line 2—2, Fig. 1, the said figure illustrating the position of the parts at the beginning of the stroke; Fig. 3 is a sectional view similar to the lower part of Fig. 2, illustrating the position of the parts at the beginning of the drawing operation; Fig. 4 is a similar view illustrating the position of the parts at the completion of the drawing operation and before the withdrawal of the plunger. Fig. 5 is a similar view illustrating the position of the parts after the plunger is withdrawn and before the blank-holder is elevated to discharge the stamping from the die.

The press in connection with which I have illustrated my invention has a reciprocating plunger A, a stationary die B, and a movable blank-holder C. Means are provided whereby the blank-holder clamps the blank D firmly against the punch or plunger A when the plunger hits the blank preliminary to the drawing operation, and whereby the said blank-holder thereupon moves in unison with the plunger during the drawing operation, during which time the blank is firmly clamped against the bottom of the plunger. At the conclusion of the drawing operation the plunger is withdrawn, and the blank-holder then remains in the position shown in Fig. 5. Thereupon, after the plunger is withdrawn from frictional contact with the stamping, the blank-holder is given an independent movement by which it acts as a knock-out and discharges the stamping from the die. In carrying the said invention into effect I preferably mount the blank-holder upon a blank-holder frame, which, as shown, as a whole, I designate E, and which is composed of two relatively movable parts, to wit, an upper frame E¹ upon which the blank-holder C is mounted, and a lower frame E². These two frames are connected by toggles F, of which three are illustrated. The links of the toggles are preferably joined together in suitable manner, as by a toggle link G. The frame E is suitably connected to the plunger operating crank shaft H to be moved therefrom, and this connection may be accomplished by means of connecting rods I, of which four are illustrated, by which the said blank-holder frame is connected to the plunger carrying crosshead J which is driven from

cranks H^1 on the crank shaft H by pitmen K .

An important part of my invention resides in the means whereby the toggles F 5 are controlled, so that the blank-holder may move in unison with the plunger during the drawing operation and independently thereof when acting as a knock-out. As illustrated, such means comprise a revolving cam 10 L associated with the crank shaft H ; as for instance, by being formed in the driven gear M . This groove is so formed as to give the desired motion to a stationary cam roller N which is located therein and is attached 15 by link U to rocking arm P which is keyed on rocking shaft Q which is journaled in the base of the machine. Fixed upon the shaft Q is a toggle-operating rocking arm R which is provided with a slot S in which slides a 20 pin T that is suitably fixed upon the toggle link G .

The operation of the said invention is as follows: In the starting position of the machine, illustrated in Fig. 2, the cranks H^1 25 are at the upper parts of their path of rotation wherein the plunger A is withdrawn from the work, as illustrated in Figs. 1 and 2. At this time the cam is in a high part of the groove, so that the blank-holder C is 30 substantially in contact with the blank D . Thereupon the crank shaft will revolve counter-clockwise, as seen in Fig. 2, causing the punch to descend until it engages the blank. During this time the cam groove has 35 a slight rise L^1 which straightens the slotted arm R to a vertical position, as seen in Fig. 3, wherein the toggles are straightened. This straightening of the toggles raises the blank-holder C as the frame E descends, and 40 causes the same to remain in position against the under side of the blank, so as to press the same firmly against the plunger when it hits the blank. During the drawing operation the cam groove has a dwell maintaining 45 the toggles straight and permitting the frame E carrying the blank-holder to be moved in unison with the plunger by means of the connecting rods I , and the pin T sliding in the slot S enables the blank-holder to 50 move in unison with the plunger and to at all times firmly press the blank against the bottom of the plunger. At the conclusion of the drawing operation the parts are in 55 the position shown in Fig. 4, wherein the plunger has pressed the blank to its desired shape and the pin T is near the bottom of the slot S . At this time the cranks H^1 are in their lowest position. Thereupon the plunger will be withdrawn, as seen in Fig. 5, 60 and the friction between the stamping and the die being greater than the friction between the plunger and the stamping, the stamping will remain in the die. The crank shaft when it withdraws the plunger from 65 frictional contact with the stamping at the

same time lifts the blank-holder frame E . At this time, however, the cam roller N rides down the fall L^2 in the cam groove, depressing the link U and rocking the shaft Q to break the toggles, as seen in Fig. 5, so that 70 the blank-holder does not at this time begin to move the blank from out of the die. The frame E , being now in its upper position, a continued rotation of the crank shaft will cause the cam roller to ride up on the rise L^1 75 in the cam groove, straightening the toggles sufficiently so that the blank-holder acts as a knock-out and discharges the drawn shell from the die. At this time the parts are in the position illustrated in Fig. 2, wherein the plunger is withdrawn from the stamping 80 and the toggles are not quite straightened.

In the particular construction of press illustrated the crank shaft is located at the upper part of the frame V and the plunger 85 is driven down upon the work which is held on the die B on the bed or base W of the machine. The plunger-carrying crosshead J is mounted to slide in ways X on the frame V . The blank-holder C is supported upon 90 the upper frame E^1 by suitable posts Y . The rocking shaft Q is journaled in the base 95 of the machine. The crank shaft H is driven by a pinion Z on driving shaft Z^1 . The arm P , rock shaft Q , and arm R , in effect constitute a bell-crank lever, and the operation of this is such that the toggles are always straight when the plunger hits the blank, and at this time the slotted connection permits the blank-holder to descend with the 100 plunger. The slotted connection in the arm R permits of an adjustment to accomplish 105 a greater break of the toggles when it is desired, in case a deeper stamping is to be drawn.

I have illustrated in the accompanying drawings the most desirable manner of constructing my invention now known to me, but the invention is not necessarily limited thereto, as numerous modifications may be 110 made therein and equivalent devices for those illustrated employed, within the limits of the appended claims.

What I claim is:

1. In a drawing press, a plunger, operating means therefor, a blank-holder frame, a blank-holder adapted to clamp the work against the plunger, said blank-holder mounted in said frame and movable relative thereto, a connection to said operating means for moving said blank-holder and frame together, and means for moving said blank-holder relative to its frame. 115

2. In a drawing press, a plunger, operating means therefor, a blank-holder frame, a blank-holder adapted to clamp the work against the plunger, said blank-holder mounted in said frame and movable relative thereto, a connection between said operating means and said blank-holder frame, 120

125

130

and means between said operating means and said blank-holder for moving said blank-holder relative to its frame.

3. In a drawing press, a punch, a die, a blank-holder adapted to clamp the blank against the punch in its working stroke and to be moved as the punch moves, and means for moving the blank-holder to discharge the work from the die after the punch is withdrawn from frictional contact with the stamping.

4. In a drawing press, a punch, a stationary die, a blank-holder within said die, means for causing the blank-holder to clamp the blank against the punch in its working stroke, said means permitting the blank-holder to move as the punch moves, and means for moving the blank-holder to discharge the work from the die after the punch is withdrawn from frictional contact with the stamping.

5. In a drawing press, a plunger, a shaft therefor, a blank-holding frame connected to said plunger, a blank-holder, toggles between said frame and blank-holder, a rocking arm mounted in a fixed part of the press and rocked from said shaft, and having a slotted connection with said toggles.

6. In a drawing press, a plunger, a movable blank-holder frame, a blank-holder adapted to clamp the work against the plunger, said blank-holder mounted in said frame and movable relative thereto, means for moving said blank-holder and frame in unison with said plunger, and means for moving said blank-holder relative to said frame out of unison with said plunger.

7. In a drawing press, a movable blank-holder frame, a blank-holder in said frame, toggles between said blank-holder and frame, means for operating said toggles, said blank-holder movable with said frame and adapted to be moved relatively thereto by said toggles.

45 8. In a drawing press, a plunger, a crank shaft therefor, a movable blank-holder frame, a blank-holder in said frame and movable relatively thereto, a connection from said crank shaft to said blank-holder frame for moving the same in unison with the plunger, toggles between the blank-holder and frame, and an operating connection thereto from the crank shaft, said blank-holder adapted to be moved relatively 50 to said blank-holding frame and out of unison with the plunger by said toggles.

9. In a drawing press, a plunger, a crank shaft therefor, a movable blank-holder frame, a blank-holder in said frame and movable relatively thereto, a connection from said crank shaft to said blank-holder frame for moving the same in unison with the plunger, toggles between the blank-holder and frame, and an operating connection thereto from the crank shaft, com-

prising a rock shaft, a rocking arm on said rock shaft adapted to control said toggles, and a connection to said rock shaft from said crank shaft.

10. In a drawing press, a plunger, a crank shaft therefor, a movable blank-holder frame, a blank-holder in said frame and movable relatively thereto, a connection from said crank shaft to said blank-holder frame for moving the same in unison with the plunger, toggles between the blank-holder and frame, an operating connection thereto from the crank shaft, comprising a rock shaft, a rocking arm on said rock shaft having a slotted connection with the link of said toggles, and a connection to said rock shaft from said crank shaft.

11. In a drawing press, a movable blank-holder frame, a blank-holder in said frame, a plurality of toggles between said blank-holder and frame, a bar connecting the links of said toggles, said blank-holder movable with said frame and adapted to be moved relatively thereto by said toggles.

12. In a drawing press, a plunger, a movable blank-holder frame, a blank-holder in said frame, a plurality of toggles between said blank-holder and frame, a bar connecting the links of said toggles, said blank-holder movable with said frame and adapted to be moved relatively thereto by said toggles, a plunger, a crank shaft therefor, a rock shaft, an operating connection between said crank shaft and rock shaft including a cam and a groove associated with said crank shaft, and an arm on said rock shaft having a pin and slot connection with said bar.

13. In a drawing press, a plunger, a movable blank-holder frame, a blank-holder in said frame, said blank-holder and frame connected to move in unison with said plunger, toggles between said blank-holder and frame, means for operating said toggles comprising a rocking arm having a pin and slot connection with the link of said toggles, whereby when said rocking arm is aligned with the path of movement of said frame it permits movement of said connected frame and blank-holder, and means for rocking said arm whereby said blank-holder is moved by said toggles relatively to said frame.

14. In a drawing press, a plunger, a crank shaft therefor, a movable blank-holder frame, a blank-holder in said frame, said blank-holder and frame connected to move in unison with said plunger, toggles between said blank-holder and frame, means for operating said toggles comprising a rocking arm having a pin and slot connection with the link of said toggles, whereby when said rocking arm is aligned with the path of movement of said frame it permits movement of said connected frame and blank-holder, a cam groove associated with said crank shaft and a cam therein and connections therefrom.

- to said rock shaft for moving said blank-holder relatively to said frame by said toggles, said parts so combined and operating that the blank-holder clamps the blank 5 against the plunger during its working stroke and is moved as the plunger moves, and the blank-holder has a movement against the stamping after the plunger is withdrawn, as a knock-out.
- 10 15. In a drawing press, a plunger, a blank-holder, means for giving the blank-holder a movement in unison with the plunger dur-

ing the drawing operation, and means acting after the plunger is withdrawn from frictional contact with the stamping for giving 15 the blank-holder an independent movement to discharge the stamping.

In witness whereof, I have hereunto signed my name in the presence of two subscribing witnesses.

WILLIAM KLOCKE.
